EBULLITION-TYPE COOLER

Norman H. Gay, Los Angeles, Calif.

Application June 15, 1936, Serial No. 85,381

3 Claims. (CL 62—126)

The present invention relates to a cooler, for employment in a refrigeration plant.

One of the features of the present invention is the provision of a cooler in which the cooling agent is contained within a shell and the medium to be cooled is moved through a plurality of tubes which are positioned within the shell, and in which incoming refrigerating medium is introduced at the bottom and the flash gas formed therefrom in passing from the high pressure condition at the condenser to the low pressure condition at the cooler, is utilized for creating an active movement of the refrigerating medium within the shell.

Another feature of the present invention is the provision of a cooler having a shell and a plurality of tubes within the shell for the passage of the material to be cooled, together with a distributing header tube located within the shell for the delivery of the refrigerating medium along the length of the shell and having apertures therein for the distribution of refrigerant liquid and flash gas into the shell.

With these and other features as objects in view, as will appear in the course of the following specification and claims, an illustrative form of practicing the invention is shown in the accompanying drawing in which:

Fig. 1 is a diagrammatic view showing the assembly of the structure in a refrigerating plant.

Fig. 2 is a transverse section, on a larger scale, substantially on line 2—2, through the cooler.

The cooler of the present invention is particularly advantageous for use with certain types of refrigerating media, in which there is difficulty in maintaining a proper circulation of the refrigerant medium within the cooler itself, so that the gases formed by the vaporization of the refrigerant medium are removed from contact with the surfaces which are to be maintained cool, and are moved upward and into the discharge duct and for maintaining the desired agitation and ebullition of the liquid refrigerant. By establishing a powerful circulation within the cooler, by use of the flash gas, this difficulty is eliminated.

On the accompanying drawing, a refrigerating plant is illustrated as having a compressor C which compresses refrigerant gas and delivers it as a hot compressed gas through a conduit 10 into a condenser K, where it is cooled and liquefied and delivered into a receiver R from which it flows, usually as a hot refrigerant liquid, through a conduit 11 to the expansion valve EX. The pressure drop occurring at passage through the

expansion valve leads to the formation of a quantity of gas which is known as "flash" gas, and in the cooling of the remaining liquid refrigerant through a low temperature. Hence, a mixture of liquid and gaseous refrigerant at low temperature and relatively low pressure passes through the conduit 12 into the cooler EV in which the heat exchange occurs so that the flash gas and other gas formed by evaporation is transferred by a conduit 13 back to the compressor C for recycling.

According to the present invention, the cooler EV is provided with a horizontal cylindrical jacket or shell 15 which is closed at its ends by the head sheets 16 which are apertured to receive the tubes 17. Drums 18, 19 have flanges and are fixedly and tightly connected to the head sheets 16 and are themselves closed by end sheets 20 to provide the inlet and outlet headers for the material to be cooled. Illustratively, relatively warm water may be admitted through an inlet pipe 21 to the inlet header 18 so that it can flow through the tubes 17 to the outlet header 19 and be discharged through the outlet pipe 21a.

The conduit 12 passes through the shell 15 at a low point thereof, and is fixedly sealed thereto by welding or other suitable means. At the inner end of the conduit 12, a distributing pipe or header 25 is in communication therewith, this pipe 25 extending horizontally in the illustrated form and closely adjacent the bottom of the shell 15 and having its ends closed in this illustrative form. The header 25 has a number of apertures 26 at its top and sides for the escape of flash gas therefrom. This flash gas is usually in an intimate mixture with the incoming refrigerant liquid, so that some of this liquid is carried through these apertures 26. Larger apertures 27 are provided at the bottom of the header 25 to permit excess liquid to move into the shell 15, and thus assure the balancing of pressures between the interior of the header 25 and the interior of the shell 15, even though one or more of the orifices 26 may be blocked for any reason. Likewise, it will be understood that the apertures 26 at the top may be omitted if desired. The openings 26 at the top are preferably so small that the rate of gas escape therefrom at normal operating rates of the plant, is insufficient for the discharge of the gas through the upper holes 26 which are located adjacent the inlet conduit 12, whereby to assure a substantially uniform distribution along the length of the header 25.

The tubes 17 are located for a major portion of the cross sectional area of the shell 15, but the upper portion of this space is left free of tubes

to provide a space for the accumulation of refrigerant gas, and in which the breaking of foam may occur, with the return of the liquid refrigerant back onto the tubes 17.

5 In the form illustrated in Fig. 1, the conduits 12 and 13 are connected to the shell 15 substantially at the center of its length. Immediately beneath the mouth of the conduit 13, a baffle 30 is extended chordally across the shell 15 and welded thereto. This baffle is illustrated as substantially horizontal and as located well above the upper row of tubes 17 and operates to prevent surging of liquid refrigerant into the gas return conduit 13. In the illustrated form, the tubes substantially 10 fill the shell for the lower half of the cylinder, and for a distance above the horizontal axial plane equivalent to one-half the radius of the shell 15, while the baffle 30 is located about half way between the top row of tubes 17 and the top of the shell 15. Longitudinally of the shell 15 (Fig. 1), the baffle extends for about one-fifth of the length of the tubes 17.

In the particular illustrated form, the tubes 17 are not uniformly distributed within the portion 25 of the shell 15 occupied thereby, although it is feasible to omit some tubes in a vertical line above the header 25.

In operation, the incoming refrigerant, comprising flash gas and refrigerant liquid, enters the 30 distributing header 25 and fills the same. The flash gas seeks immediate escape through the uppermost holes 26, and thus passes into the interior of the shell 15 and causes a rapid agitating or circulating movement of the liquid refrigerant. 35 In case that there is little demand for cooling effect at the tubes 17, the valve EX is closed down and hence less flash gas is admitted, and thus a regulation of the agitation occurs with a regulation of the quantity of liquid refrigerant 40 which is being admitted to the shell; while conversely a greater demand for refrigeration leads to the delivery of a greater quantity of mixed refrigerant liquid and flash gas past the expansion valve EX into the header 25. These effects are 45 also produced according to the relative suction occurring at the conduit 13. If a greater quantity of gas is present in the header 25, the mixture is of course projected in greater volume, and a greater agitation occurs. A separation of flash gas from refrigerant liquid also occurs in the 50 distributing header 25; this flash gas passes to the top of the header 25 and escapes through the top opening 26. These openings are preferably small and insufficient for the escape of the flash gas 55 at its particular normal rate of introduction and separation, and the liquid in the header 25 is

depressed so that more flash gas may escape through lateral openings 26. As the distributing header is horizontal in the illustrated form, this results in an advantageous proportioning of the flash gas along the length of the cooler, so that 5 adequate effects are produced at all points. Thus, the gas definitely escapes from the header 25, and a type of automatic regulation occurs thereat, along with the regulation effected at the expansion valve EX and by the operation of the ex- 10 pansion valve EX.

This invention is particularly advantageous with refrigerant media of the type of Freon; and with other refrigerating media whose characteristics (such as surface tension, viscosity, etc.) are 15 such that an active agitation is desirable.

It is obvious that the invention is not limited solely to the form of the construction shown, but that it may be modified in many ways within the scope of the appended claims.

26 I claim:

1. An evaporative cooler for a refrigerating plant having means for producing liquid refrigerant under pressure and an expansion device by which the pressure of the refrigerant is reduced 25 on its way to the cooler; said cooler comprising a receptacle for the liquid refrigerant, heat exchange devices located in said receptacle, a header located within and at the bottom of said receptacle and connected to the expansion device for receiving the refrigerant therefrom, said header being of such relatively large cross-sectional area as to permit a relatively slow travel of refrigerant therethrough and consequent effective separation 30 of flash gas from the liquid thereof, said header being perforated for the discharge of the flash gas and liquid to the space within the receptacle to agitate and circulate the liquid in the receptacle, and return means for gaseous refrigerant from said receptacle to the first mentioned means. 40

2. An evaporative cooler according to claim 1, wherein said header is an elongated tubular body disposed longitudinally of the receptacle, and said perforations are relatively large for passage of both liquid refrigerant and flash gas there- 45 through.

3. An evaporative cooler according to claim 1, wherein said header is tubular and of substantially the length of the receptacle, said perforations are spaced from the top of the header and 50 relatively large for passage of both liquid refrigerant and flash gas therethrough, and a surge-preventing baffle is arranged within the receptacle adjacent said return means.
